US0D1097687S

(12) **United States Design Patent** (10) **Patent No.:** **US D1,097,687 S**
(45) **Date of Patent:** **** Oct. 14, 2025**

(54) **BLENDER CONTAINER**

(71) Applicant: **Hy Cite Enterprises, LLC**, Middleton, WI (US)

(72) Inventors: **Aric Dichraff**, McFarland, WI (US); **Jose Juan Santiago**, New York, NY (US); **Craig Stevenson**, Fitchburg, WI (US); **Terri Zeman**, Brooklyn, WI (US); **Morad Ghasseman**, Oak Park, IL (US); **Jose Shi Chun Yu**, Mettawa, IL (US)

(73) Assignee: **Hy Cite Enterprises, LLC**, Middleton, WI (US)

(**) Term: **15 Years**

(21) Appl. No.: **29/869,970**

(22) Filed: **Jan. 13, 2023**

(51) LOC (15) Cl. **07-04**

(52) U.S. Cl.

USPC **D7/413; D7/378**

(57) **CLAIM**

The ornamental design for a blender container, as shown and described.

DESCRIPTION

FIG. 1 is a top perspective view of a blender container, showing our new design;

FIG. 2 is a bottom perspective view of the blender container of FIG. 1;

FIG. 3 is a first side elevation view of the blender container of FIG. 1;

FIG. 4 is a second side elevation view of the blender container of FIG. 1 opposite the first side;

FIG. 5 is a third side elevation view of the blender container of FIG. 1;

FIG. 6 is a fourth side elevation view of the blender container of FIG. 1 opposite the third side;

FIG. 7 is a top plan view of the blender container of FIG. 1; and,

FIG. 8 is a bottom plan view of the blender container of FIG. 1.

1 Claim, 8 Drawing Sheets
